REINFORCED METAL WOOL PAD

Robert F. Seelenbinder, Springfield, Ohio, assignor to International Steel Wool Corporation, Springfield, Ohio, a corporation of Ohio

Application July 15, 1948, Serial No. 38,771

15 Claims. (Cl. 15—209)

This invention relates to cleaning or abrading pads for use on power operated equipment, and more particularly to metal wool pads for such purposes having substantially identical characteristics throughout their entire area.

Steel and other types of metal wool have many applications in household and industrial cleaning. One of its uses is in power driven machinery for heavy duty work, for example, in portable floor cleaners. These devices operate by pressing against the floor a metal wool pad and rotating the pad at high speed to accomplish by its abrasive action a scouring of the floor surface.

The pads used in connection with these machines are, for greater firmness and long life, made of strips of metal wool spirally wound or otherwise folded to the desired shape and size. For ease of handling and to prevent uncoiling during use, the several folds of the pad are interconnected. The interconnecting devices heretofore used have been transverse wires, wire stitching, welding and like relatively rigid and unyielding means. Disadvantages in assembly and expense have attended such use. In addition, pads so constructed have a relatively short useful life, since a pad must be replaced when it becomes worn to the point that the interconnecting means become worn or exposed. An exposed wire or weld is damaging to the floor surface, and moreover should such connecting means break from contact with the work, rapid disintegration of the pad results.

Thus, the object of the invention is to simplify the construction as well as the means and mode of operation of metal wool pads, whereby such pads may not only be economically manufactured, but will be more efficient in use, of longer life, and give more uniform and satisfactory results.

A further object of the present invention is to increase the useful life of metal wool pads of the kind described and to reduce the cost and difficulties of manufacture thereof.

Another object of the invention is to present a novel method of fabricating metal wool cleaning pads.

A further and more specific object of the invention is to obviate the disadvantages inherent in a wire, rod or weld reinforced pad by eliminating such connecting means.

Still another object is to form a simple and effective tie between the folds of a metal wool pad according to a method utilizing the cohesive properties of the metal wool.

A further object of the invention is to provide a metal wool pad possessing the advantageous structural features, the inherent meritorious characteristics and the method of fabrication herein described.

With the above primary and other incidental objects in view as will more fully appear in the specification, the invention intended to be protected by Letters Patent consists of the features of construction, the parts and combinations thereof, and the mode of operation, as hereinafter described or illustrated in the accompanying drawings, or their equivalents.

Referring to the accompanying drawing, wherein is shown the preferred but obviously not the only embodiment of the invention,

Fig. 1 is a view in perspective of a metal wool cleaning pad made in accordance with the present invention;

2

Fig. 2 is a view of the pad of Fig. 1 in cross-section, showing the interconnecting metal wool strands; and

Fig. 3 is a view of a partly assembled pad, showing a method of inserting the transverse strands therein.

Fig. 4 shows the twisted relation of the filaments comprising the metal wool strip, somewhat exaggerated for clarity, and a modified form of interconnection between the adjacent contacting layers of the strip.

Like parts are indicated by similar characters of reference throughout the several views.

According to the instant invention, there is substituted for the wire, rod or welded tie members of the prior art, interconnecting strands made of the same material as the pad itself. The strands are introduced into the folds of the pad as disconnected transverse threads, and, being of the same material as the pad, intermesh therewith so as to resist separation of the folds and withdrawal of the strands.

Evident advantages flow from such a construction. The interconnecting strands become in effect an integral part of the pad and present no obstacle to a full use of the whole of the pad. Parting of a strand, as a result of wear, has but a localized effect and by the time complete disintegration of the connectors takes place, the remainder of the pad is so thoroughly matted that separation thereof into its original folds is impossible.

Cleaning pads of the kind to which this invention relates usually are made by coiling a continuous strip of metal wool fibre upon itself. As shown in the drawings, the instant invention is disclosed in connection with a pad so formed. As will be clear from the following description, however, the invention is not so limited but is applicable to pads otherwise folded and to those made up of a plurality of disconnected strips.

Referring to Fig. 1, the illustrated embodiment of the invention comprises a coiled strip 10 of steel or other metal wool fibre. The strip is made, according to conventional practice, of numerous filaments or rovings arranged generally parallel to one another and loosely entwined or matted together to form an elongated continuous strip of the desired width and thickness.

The strip 10 is coiled upon itself in a single plane and as so spirally wound presents a disc-like appearance with adjacent convolutions or layers in contact with one another. One of the flat sides of the pad so formed becomes the working surface. The pad is so mounted or arranged in relation with the machine as to present such surface to the work, the pad being held in the machine by gripping devices or other means not pertinent to this disclosure.

As shown in Fig. 2, the pad includes, in addition to the strip 10, two transverse connecting strands 11 and 12. The strands 11 and 12 are made of filaments of steel or other metal wool like that used in forming the strip 10 and extend radially through all the successive folds of the coiled strip at right angles to the axis of the pad. The filaments making up the strands 11 and 12 are loosely entwined or matted together, like those of the strip 10.

The respective filaments of the strands and strip being at right angles to one another and in intimate contacting relation, intermeshing and entanglement occurs effective to resist uncoiling of the strip and withdrawal of the strands. The number, placement and size of the interconnecting strands may vary with the size of the pad but in most instances two strands placed at right angles to one another and proportioned as to size as roughly indicated in the drawing provide a satisfactory connecting means.

The strands 11 and 12 are inserted into the pad following forming and coiling of the strip 10. One manner of effecting such introduction is shown in Fig. 3, wherein a needle 13 is illustrated as drawing a strand 12 through the pad. According to this method, a needle of suitable size, having threaded therein one end of a strand of the steel or other metal wool, is inserted into the peripheral edge or outer fold of the pad, passed through intervening folds and out at a point diametrically opposite its place of entry. The strand of metal wool is then pulled transversely through the pad, and, when projecting portions appear, such portions are trimmed adjacent the peripheral

edge of the pad. A contained connector strand thereby remains embedded in the pad as indicated in Fig. 2. In the insertion of two strands as shown, which preferably intersect adjacent the center of the pad, two such stitches as described are taken, the second about ninety degrees distant from the first.

The loosely matted wool of the strip 10 does not offer material resistance to passage of the needle 13 therethrough, but such work is aided, particularly that part of the stroke during which the strand is drawn through the folds of the strip, if the needle is power driven.

In connection with the threading of the strands through the coiled strip 10, it will be understood that the path of the strands may be irregular or sinuous rather than straight. The cohesive properties of the metal wool, however, will ordinarily make such modification unnecessary.

During formation of the metal wool strip 10 by gathering together the individual filaments, the strip is twisted thereby placing the individual filaments in a helical position throughout the area of the strip. Such twist (slightly exaggerated in Fig. 4 for clarity) is produced prior to the coiling of the strip 10 into the finished pad. The twist which is imparted to the filaments comprising the strip 10 provides a diagonal stroke at all times to the surface being treated, since as the pad revolves the individual filaments of metal wool are disposed in diagonal relation to the path of movement rather than being tangential thereto. Such diagonal motion has proved to be quite advantageous in producing a more efficient pad of longer life.

There is also shown in Fig. 4 a slightly modified construction in which the connecting strand 12a is substituted for the former strand 12. The only difference in the two forms of pad is that the strand 12a of Fig. 4 constitutes a continuation of the strip 10 rather than a separate strand 12 as shown in Figs. 1 to 3, inclusive. The strand 12a is threaded through the convolutions of the pad in the same manner as is the strand 12, the end of the strip 10 being inserted in the needle 13 or other threading instrument. The strand 11 is the same as that used in the form shown in Figs. 1 to 3, inclusive.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. A pad for floor cleaning and the like, including a strip of metal wool fibre arranged in a coil with adjacent layers thereof in contacting relation, and strands of similar metal wool fibre extending transversely through said layers and at right angles to each other, said strands intersecting one another at approximately the middle of the pad and the outer ends of the strands terminating adjacent the peripheral edge of the pad.

2. A metal wool pad including multiple layers of metal wool, each layer comprising a plurality of individual filaments arranged in substantially parallel helical relation, the multiple layers of metal wool being arranged in adjacent contacting relation with each other, and means interconnecting the adjacent layers of metal wool into an integral substantially homogeneous mass including strand means of like metal wool extending transversely of the layers, the individual filaments of which are intertwined with the filaments of the layers.

3. A metal wool pad, including a strip of metal wool fibre arranged in a coil with adjacent layers thereof in contacting relation, and a connector strand of similar metal wool fibre extending transversely through said layers, said coil and connector strand producing a substantially homogeneous pad having identical characteristics throughout its entire area.

4. A pad including a strip of metal wool comprising a plurality of helically twisted metal wool fibres arranged in a coil, and a strand of metal wool fibre comprising an

end of the metal wool strip extending transversely through the coils and intermeshing therewith to resist uncoiling of the pad.

5. As an article of manufacture, a pad, including continuous strips of metal wool fibre arranged in folds, adjacent folds of which are in contact with one another, and strand means of a material which is the same as that of said strip extending transversely through said folds, the filaments of said strip and said strand means entangling to resist unfolding of the pad.

6. A metal wool pad, comprising a continuous strip of metal wool fibre arranged in folds, adjacent folds of which are in contact with one another, and one or more strands of metal wool fibre extending transversely through said folds and resisting change of shape of the pad by entanglement with the material of said folds, said strip and said strands producing a substantially homogeneous pad having identical characteristics throughout its area.

7. A pad according to claim 6, characterized by a plurality of said transverse strands unconnected to each other and having their opposite ends terminating adjacent the peripheral edge of the pad.

8. The herein described method of making a metal wool pad, comprising the steps of forming a continuous strip of metal wool fibre from a plurality of individual rovings arranged in substantially parallel relation, folding said strip upon itself to a desired shape with adjacent layers in contact with one another, and passing transversely through said layers one or more strands of metal wool.

9. The herein described method of making a metal wool pad, comprising the steps of forming a continuous strip of metal wool fibre, folding said strip upon itself to a desired shape with adjacent layers in contact with one another, threading transversely through the layers of said strip one or more strands of similar metal wool fibre, the strands entangling with said strip to resist unfolding of the pad, and trimming projecting ends of the strands adjacent the peripheral edge of the pad.

10. A metal wool pad, including multiple layers of metal wool fibre, adjacent layers of which are in contact with one another, and interconnecting strand means of metal wool fibres extending transversely through said layers, separation of said layers and withdrawal of said strand means being resisted by entanglement and cohesion of the respective metal wool filaments.

11. A metal wool pad including multiple contacting layers of metal wool comprising a plurality of individual filaments arranged in substantially parallel relation, and metal wool strand means extending transversely thereof in entangled relation with the filaments of the layers, the entangled relation of the strand means and layers preventing separation of the layers one from another.

12. The herein described method of manufacturing a metal wool pad, including the steps of arranging a plurality of individual filaments of metal to form a strip of metal wool, arranging said strip of metal wool in adjacent contacting layers, forming an additional plurality of individual filaments of metal into a strand of metal wool, and interconnecting the adjacent contacting layers of metal wool by entangling the metal wool strand therewith in transversely disposed relation thereto.

13. A metal wool pad including a plurality of individual metal wool filaments loosely arranged in a helical formation to produce a metal wool strip coiled upon itself with adjacent layers thereon in contacting relation and transverse tie members of similar material extending through the contacting convolutions of the pad, at least one of said tie members comprising the end portion of the metal wool strip.

14. A metal wool pad, including a strip of metal wool fibre arranged in a coil with adjacent layers thereof in contacting relation, and a transverse tie member passing through the adjacent layers thereof to hold the coil in assembled relation, said tie member comprising the end of the metal wool strip from which the coil is formed.

15. A metal wool pad including a strip of twisted metal wool fibre arranged in a coil with adjacent layers thereof in contacting relation, and tie members of similar material passing transversely through the contacting layers thereof, the construction and arrangement being such that the strip of twisted metal wool fibre at all times presents a working surface disposed in angular relation to its direction of motion.
